Barlett Browne.

UNITED STATES PATENT OFFICE.

GEORGE H. HART, OF WEST HARTFORD, CONNECTICUT.

SWITCH-CONTAINING PLUG-CONNECTOR.

1,266,801.

Specification of Letters Patent.

Patented May 21, 1918.

Application filed June 20, 1916. Serial No. 104,719.

To all whom it may concern:

Be it known that I, GEORGE H. HART, a citizen of the United States, residing at West Hartford, county of Hartford, State 5 of Connecticut, have invented certain new and useful Improvements in Switch-Containing Plug-Connectors, of which the following is a full, clear, and exact description.

My invention relates to improvements in 10 electric switches and more particularly to switch containing plug connectors for connecting electric flat irons and other heating appliances in circuit. It has for its object to provide a connecting plug within which 15 is a switch for controlling the current supplied to the heating appliance. It also has for its object to provide means for relieving the projecting terminals of a heating appliance from strain when the plug is in position. It also has for its object to provide 20 improvements in the switch mechanism used within the plug as referred to in the claims.

The following is a description of an embodiment of my invention, reference being 25 had to the accompanying drawings, in which:

Figure 1 shows a side elevation of an electric flat iron including the connecting plug.

Fig. 2 is a rear view of a part of the 30 handle on an enlarged scale.

Fig. 3 is a front elevation of the connecting plug.

Fig. 4 is a lower end view of the plug showing the terminal sockets.

Fig. 5 is a detail of a combined separator 35 and dowel forming part of the plug.

Fig. 6 is a section of the base of the plug on the line 6—6, Fig. 1, the mechanism being shown in full.

Fig. 7 shows one of the two separable 40 halves of the plug with the switch mechanism removed.

Fig. 8 shows the other separable half of the plug.

Fig. 9 is a detail of the switch arm operating mechanism and support therefor; and,

Fig. 10 is an end view of the parts of Fig. 9 looking toward the right hand end thereof with parts broken away.

Referring more particularly to the drawings, 1 is the base of an electric iron having a handle grip 2 connected to the base by flat metal uprights 3. The base is provided with the ordinary heating coils (not shown), 55 and also in the well known manner with two projecting terminals 4, as shown in dotted

lines in Fig. 1. The plug is elongated, as shown in Fig. 3, and consists of two base members 5—5', being separable on a plane which passes through the line 6, into two 60 similar halves. The plug is of such shape, as shown in Fig. 4, that a section thereof at right angles to its longer axis is itself elongated in shape and the plane just referred to coincides with the shorter axis of 65 this elongated section. These two halves are made of insulating material and are held together by a clamp 7 which surrounds both halves and is tightened by a screw 8. The plug is provided with a headed stud 9, 70 which, in the construction shown, is carried by a projection 9', depending from the body of the clamp 7. This stud 9, when the plug is being inserted in place, is first passed through the upper portion of the key hole 75 slot 10 in the rear upright 3 and then slipped down into the lower portion thereof, with the result that it partially supports the plug and relieves the terminals 4 from the strain 80 which would otherwise be due to a sudden blow or pressure on the plug.

Mounted on the member 5 is a terminal plate 11, which is secured in place by a bushing and from which depend spring clips 12 forming one of the contacts of the switch. 85 13 is a binding screw for securing one of the circuit terminals. 14 is another plate secured in a similar manner, from which project upwardly spring members carrying clips 15 in line with the clips 12 and constituting the other contact of the switch. Electrically connected to the plate 14 and projecting downwardly is a spring socket 16 for engaging one of the plugs 4. The other member 5' is provided with two plates 90 11'—14' secured thereto, which plates are permanently connected electrically by a conductor 17. The plate 11' is provided with a binding screw 13' for one of the ends of the circuit. The plate 14' has connected to it a depending socket 16' for receiving the other of the plugs 4. Between the two halves 5—5' a coil spring wire is clamped in the ordinary manner to surround and protect the flexible conductor 105 leading to the heating elements of the iron.

At the lower ends of the halves 5—5' are formed recesses containing projections 18—18'. In these recesses the two halves of the combined separator and dowel 19 fit, 110 the projections 18—18' passing into the recesses 20 in the sides of this dowel. The

member 19 not only acts as a dowel for positioning the two lower ends of the two halves but, being of insulating material, also electrically separates the sockets 16—16' 5 and the plates 14—14'.

In order to electrically connect and disconnect the terminals 12 and 15 so as to control the circuit through the iron, I provide switch mechanism incased within the 10 connecting plug, consisting of a U-shaped frame having two upright members 21—22, the member 22 having a lateral extension which is secured to the member 21 and provided with a slot 23. These two members 15 21—22 are provided with openings, through which pass the ends of an actuating member 24 containing springs 25 and anti-friction balls 26. This actuating member 24 is longitudinally slotted and within its slot is 20 located the lower end of a switch arm 27 pivoted to the actuating member at 28. The lower end of this switch arm has a projection 29 which, as the actuator is moved, moves in and is guided by the slot 23 in the lower portion, the same acting to align and steady the moving parts. The lower end of the switch arm is also provided with cams 30—30 which co-act with the anti-friction balls in the operation of the switch. 25 The upper end of the switch arm is provided with two contact engaging members 31, which are insulated from the switch arm 27 but are electrically connected together. The upper end of the switch arm 27 is also 30 provided with forward and lateral extensions 32—32' which alternately engage the upright portions 21—22 to assist in the throw of the switch arm, as will be herein-after described. The switch mechanism is 35 supported entirely upon the member 5, the base 5 being recessed at 32 so as to receive portions of the member 21 and hold the same in alignment. A screw 34 passes through the hole 35 and securely fastens 40 the actuating mechanism to the member 5 in its aligned position. After the switch mechanism has been secured to the member 5, the member 5' is placed in position and the two are clamped together by the clamp 45 7, whereupon the plug is ready for use. The clamp 7 can be adjusted so as to be positioned at any desired point.

The switch arm actuating mechanism is similar in some respects to that described in my Patent No. 1,139,278 granted May 11, 55 1915. It is, however, carried by the U-shaped frame 21—22 which is removably secured to the base carrying the switch contacts, and the switch arm is guided by the slot 23 therein engaging the projection 29 so that these parts are self contained. The opening in the member 21 through which actuating member 24 passes, is cut away on one side so that the actuating member 24 60 65 when complete with its balls and springs

can be easily inserted. The projections 32—32' engage the upper ends of the parts 21 and 22 and hold the blades 31 out of contact therewith. The projection 32 is so short as not to withdraw the blades 31 from the contacts before the quick opening action takes place. The projection 32' is longer and so shaped as to cause the upper end of the arm to move to the left (Fig. 9) when the actuator is moving toward the right. 70 75 This shortens the necessary throw of the actuator.

The stud 9 holds the plug so close to the engaged upright of the handle that the sockets 16 are slightly distorted in a forward direction when pushed over the plugs 4—4. This results in causing the head of the stud 9 to grip the handle producing such friction at that point as to assist in holding the handle in place. 80 85

In operation when the parts are in the position shown in Fig. 6, pressure upon the left end button moves the actuating member and forces the enlarged portion at the upper end of the switch arm against the member 22 90 until the high points of the cams 31—31' pass the anti-friction balls 26, whereupon those balls, together with their actuating springs, co-act to force the switch engaging portions 30 into engagement with the terminals 12 and 15. When the switch is actuated by pressure on the other end of the actuating member, the reverse movement takes place. 95

As will be evident to those skilled in the art, my invention permits of various modifications without departing from the spirit thereof or the scope of the appended claims. 100

What I claim is:—

1. A connection plug comprising two separable elongated members of insulating material constituting an elongated plug body whose cross-section, transverse to its longest axis, is elongated, two binding posts and sockets and means for electrically connecting 105 said sockets to said binding posts, respectively, and a clamp surrounding the longest axis of said plug and holding the two members thereof in fixed relation to one another, and support engaging means carried by said 110 clamp. 115

2. A connection plug comprising an elongated base whose cross-section, transverse to its longest axis, is elongated, said base being separable into two parts along a plane 120 passing through the shorter axis of said elongated cross-section, a binding post, socket and means for electrically connecting the same together, all carried by one of said two parts, a binding post, socket and means 125 adapted to include a snap-acting switch for making and breaking an electrical connection between said last named binding post and its socket, all carried by the other of said two parts, and means for holding said 130

two parts together in fixed relation to one another.

3. A connection plug comprising an elongated base whose cross-section, transverse to its longest axis, is elongated, said base being separable into two parts along a plane passing through the shorter axis of said elongated cross-section, a binding post and a socket and means for electrically connecting 10 the same together, all carried by one of said two parts, a binding post, socket and means
- adapted to include a snap-acting switch for making and breaking an electrical connection between said last named binding post and its socket, all carried by the other part, 15 and an adjustable clamp surrounding the longest axis of said base, said clamp holding said parts in fixed relation to one another, and support engaging means carried by said clamp.

GEORGE H. HART.
